US00D438787S

(12) **United States Design Patent** (10) Patent No.: **US D438,787 S**
Heeter et al. (45) Date of Patent: ** *Mar. 13, 2001

(54) **TUBE**

(75) Inventors: **Kristina B. Heeter**, Grand Rapids, MI
 (US); **Thierry Francois DeBaschmakoff**, Paris (FR)

(73) Assignee: **Amway Corporation**, Ada, MI (US)

(*) Notice: This patent is subject to a terminal disclaimer.

(**) Term: **14 Years**

(21) Appl. No.: **29/110,508**

(22) Filed: **Sep. 8, 1999**

(51) LOC (7) Cl. **09-01**

(52) U.S. Cl. **D9/302**

(58) Field of Search D9/302, 529, 521;
 222/92, 105, 107, 212, 213
